UNITED STATES PATENT OFFICE.

NORMAN E. GEE, OF ALTOONA, PENNSYLVANIA.

LIQUID-COOLING APPARATUS.

1,320,130.

Specification of Letters Patent.

Patented Oct. 28, 1919.

Application filed May 25, 1917. Serial No. 170,935.

To all whom it may concern:

Be it known that I, NORMAN E. GEE, a citizen of the United States, residing at Altoona, in the county of Blair and State of Pennsylvania, have invented certain new and useful Improvements in Liquid-Cooling Apparatus, of which the following is a specification.

This invention relates to liquid coolers for 10 railway locomotives, and particularly to electric locomotives which are designed and built for single phase distribution and three-phase current utilization, wherein there is used a sodium carbonate solution known as 15 electrolyte, in connection with the elements that are used to control the currents in the motor primaries and also the motor secondaries.

The primary object of this invention is 20 to provide an adequate electrolyte cooling apparatus through which the electrolyte is caused to circulate by means of centrifugal pumps while a current of air is caused to pass over the electrolyte as it passes through 25 the cooling apparatus, thus cooling the fluid and at the same time conducting the heat thus generated to the atmosphere above the cooling apparatus.

Another object of this invention is to provide 30 means whereby the cooling medium can readily be circulated through the electrolyte, while the cooling medium and the electrolyte move in opposite directions.

A further object of this invention is to 35 provide inclined cooling trays each of which is constructed with a plurality of fluid dividing means, which make it possible for the cooling medium to pass upward through the cooling system over each individual tray, 40 thus effectively cooling the electrolyte.

With these and many other objects in view which will be more readily apparent as the nature of the invention is better understood, the same consists of the novel construction, combination and arrangement of 45 parts as will be hereinafter more fully pointed out, illustrated and claimed.

It will be quite readily understood by those skilled in the art to which this invention 50 belongs that the same is susceptible to some structural changes and modifications without departing from the spirit or scope of the invention, but a preferred and practical embodiment of the present invention is 55 shown in the accompanying drawings, in which—

Figure 1 shows a portion of a longitudinal section of an electric locomotive with the present invention installed therein.

Fig. 2 shows a plan view of the cooling 60 tower shown in Fig. 1.

Fig. 3 shows a side elevation of one of the cooling towers.

Fig. 4 shows a portion of an end elevation of the cooling tower. 65

Similar reference characters designate corresponding parts throughout the several figures of the drawings.

In carrying out the present invention, it is proposed to provide an electrolyte tank 70 designated in its entirety by the reference character 10, which is adapted to contain the sodium carbonate solution, and has in communication therewith suitable circulating pumps 11 through a conventional valve arrangement, not shown. These pumps 11 have associated therewith the delivery pipe sections 12 and 12^a respectively leading to the compartments known as the electrolyte chambers, and designated by the references 80 13 and 14. These chambers are separate from the electrolyte tank 10, but are in valved communication therewith by means of the valves *a*—*b*, *c*—*d*, as shown in the drawings, and the arrangement of these 85 valves is such that when the valves are down, electrolyte can pass from the compartment 13—14 back into the tank 10, but when the valves are elevated, the pumps will fill the chambers with electrolyte until a certain level is reached and then the valves *a*—*b*, and *c*—*d* will open to let the electrolyte therein again flow back to the tank. 90

Between the electrolyte chambers 13 and 14, are arranged suitable cooling towers for 95 the electrolyte. A cooling tower is provided for each chamber, and as will be observed from Fig. 1 of the drawings, each tower has a pipe connection therein whose inlet end is so arranged as to receive some of the electrolyte forced by the pumps into the electrolyte chamber with the particular tower it is associated with. That is to say, the cooling tower 15, for instance, which cools the electrolyte for the chamber 13, has an upstanding tower pipe 16 therein whose lower end is so arranged with reference to the discharge end of the pipe section 12 which forces electrolyte from the tank 10 to the chamber 13, that some of the electrolyte 110 forced into the said chamber will also be forced upwardly through the pipe 16 to the

top of the cooling tower. As the electrolyte makes its way toward the bottom of the cooling tower to return to the path of electrolyte circulation caused by the pumps 11, 5 it is cooled by the novel arrangement of cooling pans and an air blast as will presently appear. The cooling tower for the chamber 14 is also provided with an upstanding pipe 17 which performs functions 10 similar to the pipe 16.

Referring now to the cooling tower wherein the temperature of the electrolyte is lowered, it will be observed that the same essentially comprises a casing having there- 15 in a plurality of superposed inclined cooling pans 18, which provide a tortuous passage for the liquid and the cooling air blast. The upstanding tower feed pipe 16, which receives electrolyte from the pump 11 through 20 the pipe section 12, communicates with a delivery trough 19 disposed transversely of the tower and arranged at the rear edge of the uppermost inclined cooling pan 18. Thus, when electrolyte is forced up through the 25 pipe 16, it will collect in the delivery trough 19, and from this pass onto the top inclined cooling pan 18. After leaving this pan, it will pass to similar successive pans until it reaches the bottom of the cooling tower 30 where it will again pass into the electrolyte circuit.

For the purpose of cooling electrolyte as it passes over the series of cooling pans in the tower, it is proposed to introduce an air 35 blast at the bottom of the tower beneath the lowermost pan. This blast of cooling air is generated by a suitable fan motor M and is conveyed to the bottom of the cooling tower through the conduit or air duct 20 where it enters said tower at the point 20^a.

To further assist in the cooling of the electrolyte as it passes through the cooling tower, it is proposed to provide suitable spreader elements at the edge of each cool- 45 ing pan. That is to say, in order that the sheet of electrolyte may be divided at spaced intervals as it discharges from the cooling pans, there is provided on each cooling pan a plurality of current dividing elements 21 which are constructed in the shape of the letter V, having the apex uppermost on the inclined surface. These current dividing elements are preferably made of sheet metal 50 which is constructed L shaped, the horizontal leg being cut and the two ends 22 brought toward each other forming the V shaped structure. The horizontal leg is used to secure the element to the pan while the upstanding vertical leg serves to divide the 55 current of electrolyte, which means that between each pan there is left a series of openings in the cataract through which the air passes on its way to the roof ventilators 23, through which the hot air and steam escape 60 to the outside atmosphere.

From the foregoing, it will be apparent that electrolyte from the tank 10 is pumped by the pumps 11 into the chambers 13 and 14 through the pipe connections 12 and 12^a respectively and when electrolyte is thus 70 pumped into the said chambers, a part thereof is forced up to the top of the tower pipe for each cooling tower. That is to say, part of the electrolyte coming through the pipe 12 for the chamber 13 is forced up 75 the pipe 16 to the top of the cooling tower 15, while part of the electrolyte for the chamber 14 is forced up the pipe 17 of the other cooling tower. When the electrolyte reaches the top of the cooling towers, it is 80 released and permitted to gravitate down a series of inclined cooling pans in opposition to a blast of cooling air supplied to the bottom of the cooling tower. Furthermore, in order to assist the cooling action, the pans 85 of the cooling tower are provided with suitable retarding means and current dividing elements as explained.

Without further description, it is thought that the many features and advantages of 90 the invention will be readily apparent.

I claim:

1. A liquid cooling apparatus including a main liquid holding chamber, a liquid receiving chamber arranged above the tank, a cooling tower also arranged above the said main liquid chamber and having means therein for causing the liquid to divide into a plurality of separate streams, a pump for elevating liquid from the main chamber to 95 the receiving chamber and to the liquid dividing means in the cooling tower, and means for supplying an air blast to the discharge end of the cooling tower whereby the air flows in opposition to the direction 100 of liquid flow.

2. A liquid cooling apparatus including a main liquid holding tank, a superposed liquid receiving chamber in valved communication with the main tank, a cooling tower arranged above the main tank and adapted to discharge therein, a pump in piped communication with the liquid receiving chamber and the cooling tower for forcing the liquid from the main tank to the receiving 110 chamber and cooling tower, and means for supplying an air blast to the discharge end 115 of the cooling tower.

3. A liquid cooling apparatus including a liquid container, a circulating pump for said container, a cooling tower having a tortuous passageway, pipe means in said tower connected with said pump for conveying a part of the liquid being circulated through the container to the upper end of 120 the tortuous passage of the cooling tower, and means for forcing air through said tower in opposition to the direction of flow 125 of liquid therein.

4. A liquid cooling apparatus including 130

in combination, a liquid container, a circulating pump connected with said container, a cooling tower having a pipe connected with said pump, and also having therein a plurality of inclined cooling pans arranged one above the other, a liquid discharge trough in communication with the tower pipe which connects with the circulating pump, a plurality of V-shaped current dividing elements secured to the discharge

edges of the cooling pans, and means for forcing an air current through the cooling tower in opposition to the direction of flow of liquid therethrough.

In testimony whereof I affix my signature in presence of a witness.

NORMAN E. GEE.
